(57) CLAIM

The ornamental design for a compact travel string instrument, as shown and described.

DESCRIPTION

FIG. 1 is a front right perspective view of a compact travel string instrument showing my new design;

FIG. 2 is a right rear perspective view thereof;

FIG. 3 is a front view thereof;

FIG. 4 is a right-side view thereof; the undisclosed left-side view being a mirror image thereof;

FIG. 5 is a rear view thereof;

FIG. 6 is an enlarged bottom view thereof; and,

FIG. 7 is an enlarged top view thereof.

The broken lines represent the portions of the design that are not part of the claim.
